Primary Examiner — Vy N Koenig*Assistant Examiner* — Kimberly Y Barnes(74) *Attorney, Agent, or Firm* — Matthew J. Spark; Stefan J. Kirchanski; Zuber Lawler & Del Duca LLP**CLAIM**

The ornamental design for an architectural fixture, as shown and described.

DESCRIPTION

FIG. 1 is a bottom, front, right perspective view of an architectural fixture, embodying the invention;

FIG. 2 is a bottom, rear, left perspective view of the architectural fixture of FIG. 1;

FIG. 3 is a front elevation view of the architectural fixture of FIG. 1;

FIG. 4 is a rear elevation view of the architectural fixture of FIG. 1;

FIG. 5 is a left elevation view of the architectural fixture of FIG. 1;

FIG. 6 is a right elevation view of the architectural fixture of FIG. 1;

FIG. 7 is a bottom plan view of the architectural fixture of FIG. 1; and,

FIG. 8 is top plan view of the architectural fixture of FIG. 1. The broken lines in the drawings represent portions of the architectural fixture that form no part of the claimed design.
